UNITED STATES PATENT OFFICE

2,596,729

FUEL IGNITION SYSTEM

Walter George See, Hammond, Ind.

Application November 5, 1947, Serial No. 784,280

7 Claims. (Cl. 158—125)

1

The present invention relates in general to fuel ignition, and has more particular reference to fuel igniters and means for operating and controlling the same, the invention having special reference to electrically actuated fuel igniters, and particularly to devices for igniting gaseous fuel in fuel burning apparatus.

An important object of the present invention is to provide an electrical fuel ignition system embodying an igniter element of material having a negative temperature coefficient of resistance, that is to say, a material in which electrical resistance decreases with increasing temperature, whereby exceedingly simple, inexpensive and effective electrical control apparatus may be employed for operating and controlling the igniter.

A further important object is to provide simple, effective, and inexpensive control apparatus for operating the fuel igniter.

Another important object is to provide simplified control apparatus which, in combination with an ignition element having negative temperature coefficient of resistance, will operate to control the delivery of fuel to a burner as and when the igniter reaches its fuel igniting temperature.

Another important object is to employ electrical current limiting means in conjunction with an igniter element having a negative temperature coefficient of resistance.

Another important object is to provide an improved mounting and support for the igniter element; a still further object being to provide fuel burning apparatus of improved construction, including a novel and inexpensive means for supporting an igniter element in the path of a fuel stream to be ignited.

Another important object is to provide improved and simplified electrical control means for operating the igniter.

The foregoing and numerous other important objects, advantages and inherent functions of the invention will become apparent as the same is more fully understood from the following description, which, taken in connection with the accompanying drawings, discloses a preferred embodiment of the invention.

Referring to the drawings:

Fig. 1 illustrates a fuel burner apparatus, more particularly apparatus for the combustion of fuel beneath the surface of a liquid to be heated, the same being a type of fuel burner in which the present invention may advantageously be incorporated.

Fig. 2 is an enlarged sectional view taken through the burner apparatus shown in Fig. 1.

2

Fig. 3 is a sectional view taken substantially along the line 3—3 in Fig. 2.

Fig. 4 is a sectional view taken substantially along the line 4—4 in Fig. 2.

Fig. 5 is a sectional view taken substantially along the line 5—5 in Fig. 4.

Fig. 6 is a perspective view of an igniter mounting element forming a part of the assembly shown in Fig. 2.

Fig. 7 and Fig. 8 are diagrammatic representations showing electrical control systems for the operation of an igniter and associated fuel supply means, in accordance with the present invention.

15 To illustrate the invention the drawings show submerged combustion apparatus 11, the expression "submerged combustion" being used herein to designate the combustion of the fuel beneath the surface of a liquid to be heated, and in direct contact with such liquid; and although the drawings show submerged combustion heating apparatus, it will, of course, be understood that the invention is not necessarily limited to submerged combustion apparatus, but may be applied wherever fuel ignition is required.

The combustion apparatus 11 comprises a burner shown generally at 12 in position submerged beneath a body of liquid 13 to be heated in a suitable tank 14. As shown, the apparatus 20 comprises an outer casing 15 extending downwardly along the inner side of the tank wall and connecting with the burner 12 whereby the gaseous products of combustion may be discharged directly into the liquid 13 through openings 16 25 in the burner 12.

The casing 15 has an end projecting upwardly of the liquid 13 in position to receive and connect with fuel supply and ignition means through which fuel may be delivered to the combustion apparatus within the casing 15, means 40 17 being provided within the casing for igniting fuel delivered therethrough to the burner 12.

To this end, the fuel supply and ignition means 45 preferably comprises tubular means forming concentric channels, within the casing 15, including an outer channel 18, a central channel 19, and an intermediate channel 20 extending between the central and outer channels. These channels 50 may be formed between tubular wall members including an outer member 15', adapted to fit within the casing 15, and concentrically disposed inner members 21 and 22 within said outer member, said members being preferably integrated in any suitable or convenient fashion as by connection thereof in a fitting 23, forming a part of the assembly mounted on the casing 15 in posi-

tion above the level of the liquid 13. The lower ends of the members 21 and 22 may be held in concentric relationship the one with respect to the other, and with respect to the outer member 15, by means of spacing collars 24 applied at the terminal ends of the members 21 and 22, which spacing collars allow for the free flow of fuel and air, respectively, through the concentric passageways 18 and 20, into the member 15' below the spacing collars for delivery thence to the burner 12, through the casing 15.

The fitting 23, as shown more particularly in Fig. 4 of the drawings, may provide for the threaded or welded connection of laterally extending conduits 18' and 20', respectively for delivering fuel and air to the concentric channels 18 and 20.

The fitting 23 provides for the connection of the central channel 19, in an axial direction with a chamber 25 formed at the end of the fitting 23 as by securing thereto, or integrally forming thereon, a preferably sleeve-like member 26, said member providing, as shown more particularly in Fig. 3, for the connection of the chamber 25 with a laterally extending pilot air supply pipe 27. The sleeve-like member 26 and the fitting 23 may, of course, be formed as separate elements secured together in any convenient or suitable fashion as by bolts, although, for the sake of convenience, it is preferable to form them as an integral unit. A preferably removable cover 28 may also be provided for closing the chamber 25, and said cover may provide an inlet chamber 29 connecting with a pilot fuel supply conduit 30 and communicating, as by means of a pipe 31, through the chamber 25 with the interior of the channel 19 substantially below the chamber 25.

The principal elements of the burner thus comprise the outer passageway 18 through which the main supply of fuel may be introduced to the burner, the intermediate passageway 20 through which the main supply of air may be introduced, the pipe 31 through which a supply of pilot fuel may be introduced into the central conduit 19 in the vicinity of the igniter 17, and there burned in air supplied through the conduit 27 and chamber 25 into the conduit 19. Upon ignition, the pilot fuel will burn at the lower end of the conduit 19 in position to ignite main fuel within the outer member 15' below the lower end of the central channel 19. In submerged combustion equipment, it should be understood that the air and fuel must be supplied at pressures great enough to overcome the head pressure of liquid at the burner; and any suitable apparatus may be utilized for the purpose of delivering fuel and air at required pressures and volumetric rates through the conduits 18', 20', 27 and 30. To this end any suitable or preferred air and fuel delivery devices may be employed, such delivery apparatus, where gaseous fuel is involved, preferably comprising means for supplying the fuel at desired pressure to the conduits 18' and 30, including electrically operated control valves in the fuel supply pipes 18 and 30, air supply being conveniently provided as by means of electrically controllable blower equipment and air flow regulating valves in the air supply conduits 20' and 27.

The igniter 17 preferably comprises a bar or rod 32 of material having a negative temperature coefficient of electrical resistance, the bar 32, to this end, preferably comprising a carbon compound such as silicon carbide. A bar suitable for

the purpose may comprise approximately 85% silicon carbide and 15% elemental silicon, by weight, the silicon carbide component being preferably in the form of a continuous reticular skeleton, in which the unit crystals are minute, uniformly distributed, and of cubic formation. The silicon component preferably comprises elemental silicon which completely fills the interstices of the silicon carbide skeleton. Such material may conveniently be produced in bars or rods of desired length and sectional configuration. Such bars will withstand exceedingly high operating temperatures without disintegration or material deterioration. The material will not fuse at excessively high electrical overloads. It is non-corrosive and substantially inert to the destructive effects of fuel combustion products. The material described, moreover, does not soften at high temperature and is self supporting over long spans, span length being limited only by the mechanical strength of the element itself, which, of course, is a function of the sectional area of the element.

The rod or bar 32 may be easily mounted, with 25 in the central conduit 19, in position to ignite fuel delivered through the pipe 31, by attaching the bar, at its opposite ends, to a pair of support stems 33 of electrical conducting material. These stems in turn may be mounted within and insulated from the fitting 23 in any suitable or preferred fashion. As shown, the fitting 23 provides an annular seat 34, facing into the chamber 25 at the end of the central channel 19 where said channel connects with the chamber 25. A mounting member, as shown more particularly in Fig. 6, is provided for supporting the stems 33 on the fitting 23. This mounting member or holder 35 may comprise any suitable preferably heat resistant electrical insulating material, such as porcelain, forming a central hub 36, defining an axial channel 37 and radially extending flanges 38 projecting outwardly of the hub 36. The outer edges of the flanges 38 are adapted to fit snugly within the walls defining the channel 19, and said flanges at their upper portions are formed with projecting lugs 39 adapted to fit snugly within the walls of the chamber 25 and to rest upon the annular seat 34 whereby to support the member 35 within the chamber connected end of the channel 19. On one side of the channel 37 and on opposite sides of a lug 39 thereof, the holder comprises a body portion 40 having an outer surface adapted to snugly interfit with the inner surface of the walls defining the channel 19. 55 This body portion is provided with a pair of axial channels 41 adapted to snugly receive and hold the stems 33 and thus support the same in the fitting 23. The stems 33 have ends projecting upwardly of the holder 35 within the chamber 25, 60 said ends being fitted with terminal means 42 adapted to electrically connect the posts 33 with electrical conductors 43 which may extend thence outwardly of the chamber 25, as through the pilot air conduit 27. The conduit 27, outwardly of the 65 housing member 26, may be provided with insulated air-tight outlets through which the conductors 43 may extend outwardly of the pipe 27 for connection with any suitable source of igniter actuating electrical power.

70 It will be seen that the central channel 37 of the holder 35 may receive the fuel inlet pipe 31 therethrough to thereby aid in supporting the pipe 31 in axially centered position within the conduit 19, whereby pilot fuel may be delivered in said conduit below the holder 35. The webbed

or spider configuration of the holder outwardly of the central hub 36 thereof affords free passage for the delivery of pilot air into the conduit 19 from the chamber 25.

The igniter may be operated by connecting the conductors 43 with a suitable source of electrical igniter energizing power. Because of its negative temperature coefficient of resistance, the igniter element 32 operates as an automatic rheostat in that it is cold and offers relatively high 10 resistance to current flow, when the actuating power is first applied. The resistance of the element 32 decreases proportionately as its temperature increases due to electrical current flow therethrough. Accordingly, if energizing power 15 at constant average potential is applied to the element, the resulting current flow therethrough increases progressively and proportionately as the element becomes heated to igniting temperature, with consequent decrease in the resistance of the 20 element. This characteristic enables the igniter, as well as the fuel supply means to the burner, to be controlled in positive fashion by an exceedingly simple electrical control system, taking advantage of the aforesaid negative temperature 25 coefficient of resistance of the igniter element.

As shown more particularly in Fig. 7 of the drawings, the igniter element 32 may be energized from a transformer 44, the secondary or output winding of which is connected with the conductors 43, the primary winding of said transformer being energized from any suitable source of electrical power 45 through suitable protective equipment 46 and a preferably manually operable control switch 47 whereby the transformer 44 may be energized from the power source 45 upon closure of the switch means 47. Since the igniter element has a negative resistance coefficient, said transformer 44, if desired, as a safety measure, may have impedance characteristics whereby to limit the current flow thereto, from the power source, to a selected maximum value. As the igniter element 32 becomes heated toward ignition temperature, current flow in the primary circuit of the transformer 44 will materially increase from the minimum value, determined by the resistance of the element 32 when cold, to a predetermined current flow value when the element 32 reaches its ignition temperature. Accordingly, the operating coil 48 of a relay switch, having normally open switch means 49, may be interconnected in the energizing circuit of the transformer 44 to cause closure of the switch means 49 as the element 32 reaches or exceeds its ignition temperature. The switch 49 may be interconnected in series with the operating solenoid 51 of a fuel flow control device such as a valve 51' disposed in the pilot fuel conduit 30 to actuate the same for the delivery of pilot fuel upon closure of the switch 49 when the ignition element has reached its igniting temperature. The relay switch, comprising the coil 48 and the switch means 49, may also include normally open, time delay closing switch means 52 adapted to be closed by the coil 48 after a predetermined time delay interval following the closure of the switch 49. The switch 52 may be interconnected in series with the operating solenoid 53 of a fuel flow control device such as a valve 53' disposed in the main fuel supply conduit 18' to actuate 70 the same for the delivery of fuel upon closure of the switch 52. Air blower or compressor means, or both, may be employed to supply air or fuel under pressure to the conduits 18', 20', 27 and 30; and such air blower or compressor means may

also be energized for operation under the control of the switch 49 or of both switches 49 and 52.

Upon closure of the switch 47, the ignition element 32 may be brought to its igniting temperature, and air and pilot fuel may be delivered through the conduits 27 and 30 as soon as the igniter element has reached its igniting temperature, whereby a pilot flame may be established at the lower end of the central channel 19 of the burner. After a time delay sufficient to assure the establishment of the pilot flame, main fuel and air may be delivered through the conduits 18' and 20' to the burner mechanism, upon closure of the switch 52, the main fuel thus supplied being ignited by the previously established pilot flame for combustion at the burner 12.

The control system shown in Fig. 7 is exceedingly simple and adapted for manual operation under the control of the switch 47. The pilot and main burner flames, having been established in the manner described, will continue in operation, barring failure of the fuel, air and electrical power supply, until the switch 47 is opened. As soon as the switch 47 is opened, or upon failure of the electrical power supply, the coil 48 will become de-energized, the switches 49 and 52 will open, thereby stopping the delivery of main and pilot fuel and air to the combustion apparatus.

Fig. 8, in addition to the equipment shown in Fig. 7, includes additional automatic switch means for disabling the igniter control circuit after establishment of the pilot flame and the ignition of main burner fuel delivered through the conduit 18', whereby, after combustion has been established, the igniter may be rendered inoperative without shutting off the supply of pilot or main fuel. To these ends a relay switch mechanism 54, having an operating coil 55, is provided, said operating coil being connected in parallel relationship with respect to the fuel control solenoid 53, under the control of the time delay closing switch 52. The switch 54 includes normally open switch means 56 and normally closed time delay opening switch means 57. The time delay opening switch means 57 is connected in the operating circuit of the relay switch coil 48 and of the transformer 44, while the normally open switch 56 is connected in a circuit to control the operating solenoid 58 of a relay switch 59, in order to actuate said switch for the closure of its normally open switch means 61 and 62 whenever the coil 58 is energized in response to closure of the switch 56. The switches 61 and 62, respectively, are interconnected in parallel relationship with the switches 49 and 52, whereby to maintain, in energized condition, the fuel and air supply means 51 and 53 upon the opening of the switches 49 and 52.

Since the switch 57 is normally closed, closure of the switch 47 will cause establishment of the pilot flame and combustion of main fuel at the burner, in the manner heretofore described. Upon closure of the switch 52, resulting in the establishment of main fuel combustion, the coil 55 will also become energized to cause immediate closure of the switch 56. Upon closure of the switch 56 the solenoid 58 will become energized to immediately close the switches 61 and 62 in parallel relationship with the switches 49 and 52. After a time delay interval sufficient to assure the establishment of the combustion of main fuel at the burner, the time delay opening switch 57 may operate to disable the igniter energizing transformer as well as the solenoid 48. Thereupon the switches 49 and 52 will open, but burner

operation will be maintained thereafter by the switches 61 and 62, which remain in closed position, thereby maintaining the solenoids 51 and 53 energized to continue the fuel supply to the burner; and the switch 62 also maintains energy in the switch operating coil 55 to hold the switch 56 closed and the switch 57 open. The burner is thus maintained in operation, barring failure of the fuel, air, and electrical power supply, so long as the switch 47 remains closed. By opening the switch 47, of course, the entire apparatus will be restored to starting condition.

Obviously, numerous modifications may be made in the control system in order to accomplish refinements in the control of the air and fuel supply, as by the addition of control relay switches and other control equipment. Essentially, however, the present invention provides benefits flowing from the utilization of the ignition element 32 having a negative temperature coefficient of resistance whereby operation of the control system is accomplished in response to increased current flow in the energizing circuit of the transformer 45 and of the switch actuating coil 48. It is desirable, of course, and especially in the manual system as shown in Fig. 7, to provide for limiting current flow to the ignition element 32, to a predetermined value appreciably in excess of that required to heat the ignition element to its igniting temperature. To this end the transformer 44 may conveniently comprise a current limiting transformer selected for the purpose of limiting at a desired value the current flow to the element 32.

It is thought that the invention and its numerous attendant advantages will be fully understood from the foregoing description, and it is obvious that numerous changes may be made in the form, construction and arrangement of the several parts without departing from the spirit or scope of the invention, or sacrificing any of its attendant advantages, the form herein disclosed being a preferred embodiment for the purpose of illustrating the invention.

The invention is hereby claimed as follows:

1. The combination, with fuel burning apparatus having associated pilot fuel delivery means and main fuel delivery means, of pilot fuel ignition means comprising an electrically operable igniter element having a negative temperature coefficient of electrical resistance, means for mounting said element in position to ignite said pilot fuel upon delivery thereof in said fuel burning apparatus, and an electrical system for actuating said igniter element and for controlling the delivery of main and pilot fuel to said burner apparatus comprising a pilot solenoid valve means for controlling pilot fuel, a main solenoid for controlling main fuel, means for energizing said igniter, a current responsive relay, responsive to current flow to said igniter element, including pilot switch means for controlling said pilot solenoid when current flow to said igniter element reaches a predetermined value and main fuel switch means operable to control said main solenoid after a time delay interval following operation of said pilot switch means, and relay switch means operable by said current responsive relay for maintaining said pilot and main solenoids in operation and for disabling said igniter element and said current responsive relay after a predetermined time delay following operation of said current responsive relay.

2. The combination, with fuel burning apparatus having associated pilot fuel delivery means

and main fuel delivery means, of pilot fuel ignition means comprising an electrically operable igniter element having a negative temperature coefficient of electrical resistance, means for mounting said element in position to ignite said pilot fuel upon delivery thereof in said fuel burning apparatus, and an electrical system for actuating said igniter element and for controlling the delivery of main and pilot fuel to said burner apparatus comprising a pilot solenoid for controlling pilot fuel, a main solenoid valve means for controlling main fuel, means for energizing said igniter, a current responsive relay, responsive to current flow to said igniter element, including pilot switch means for controlling said pilot solenoid when current flow to said igniter element reaches a predetermined value and main fuel switch means operable to control said main solenoid after a time delay interval following operation of said pilot switch means.

3. The combination, with fuel burning apparatus having associated fuel delivery means, of an electrically operable igniter element having a negative temperature coefficient of electrical resistance, disposed in position to ignite fuel upon delivery thereof in said fuel burning apparatus, and an electrical system for actuating said igniter element and for controlling the delivery of fuel to said burner apparatus comprising a solenoid valve means for controlling the delivery of fuel, means for energizing said igniter, a current responsive relay, responsive to current flow to said igniter element, including switch means for controlling said solenoid when current flow to said igniter element reaches a predetermined value, and holding relay switch means operable by said current responsive relay for maintaining said solenoid in operation and for disabling said igniter element and said current responsive relay, after a predetermined time delay following operation of said current responsive relay.

4. The combination, with submerged combustion fuel burning apparatus having associated pilot fuel delivery means and main fuel delivery means, of an electrically operable igniter element for said pilot fuel having a negative temperature coefficient of electrical resistance, disposed in position to ignite pilot fuel upon delivery thereof in said fuel burning apparatus, and an electrical system for actuating said igniter element and for controlling the delivery of main and pilot fuel to said burner apparatus comprising solenoids for controlling the delivery of fuel, current limiting means for energizing said igniter, and a current responsive relay, responsive to current flow to said igniter element, including switch means for controlling said solenoids when current flow to said igniter element reaches a predetermined value.

5. The combination, with fuel burning apparatus having associated pilot fuel delivery means and main fuel delivery means, of an electrically operable igniter element for said pilot fuel having a negative temperature coefficient of electrical resistance, disposed in position to ignite pilot fuel upon delivery thereof in said fuel burning apparatus, and an electrical system for actuating said igniter element and for controlling the delivery of main and pilot fuel to said burner apparatus comprising solenoids for controlling the delivery of fuel, means for energizing said igniter, and a current responsive relay, responsive to current flow to said igniter element, including switch means for controlling said sole-

noids when current flow to said igniter element reaches a predetermined value.

6. Fuel burning apparatus comprising means forming concentric channels for the delivery of fuel and air to a combustion chamber, including means forming a delivery channel extending from a receiving chamber to said combustion chamber, and a pipe extending axially of and having an end opening within said delivery channel, a spider-like frame of electrical insulating material mounted in said delivery channel at said receiving chamber, said frame forming a central bushing for mounting said pipe within said delivery channel, said frame providing spaced support bushings offset radially with respect to said central bushing, support stems of electrical conducting material mounted in said support bushings, an electrically operable igniter element mounted on and electrically connected with said support stems, within said delivery channel and adjacent the end of said pipe.

7. Fuel burning apparatus comprising means forming concentric channels for the delivery of fuel and air to a combustion chamber, including means forming a delivery channel extending from a receiving chamber to said combustion chamber, and a pipe extending axially of and having an end opening within said delivery channel, a spider-like frame of electrical insulating material mounted in said delivery channel at said receiving chamber, said frame forming a central bushing for mounting said pipe within said delivery channel, said frame providing

5 spaced support bushings offset radially with respect to said central bushing, support stems of electrical conducting material mounted in said support bushings, an electrically operable igniter element mounted on and electrically connected with said support stems, within said delivery channel and adjacent the end of said pipe, a laterally opening supply conduit to said receiving chamber, and conductors for electrically energizing said igniter element electrically connected with said support stems within said receiving chamber and extending outwardly thereof through said supply conduit.
